(57) **CLAIM**

The ornamental design for a car tyre, as shown and described.

DESCRIPTION

FIG. 1 is a perspective view of a first embodiment of a car tyre, showing our new design;

FIG. 2 is a front elevation view thereof, with the rear view being identical thereof, it being understood that the tread pattern is repeated throughout the circumference of the car tyre;

FIG. 3 is a left side elevation view thereof, with the right side view being a mirror image thereof;

FIG. 4 is a perspective view of a second embodiment of a car tyre, showing our new design;

FIG. 5 is a front elevation view thereof, with the rear view being identical thereof, it being understood that the tread pattern is repeated throughout the circumference of the car tyre; and,

FIG. 6 is a left side elevation view thereof, with the right side view being a mirror image thereof.

The dot-dash lines defining the sidewall, inner bead and the peripheral boundary between the tyre tread and side wall form no part of the claimed design. The other dash-dot lines illustrate portions of the car tyre that form no part of the claimed design.
